CLAIM

The ornamental design for a bag substantially as shown and described.

DESCRIPTION

FIG. 1 shows a top-front perspective view of a bag with the flap closed showing my new design.

FIG. 2 shows a rear view of the bag with the flap closed.

FIG. 3 shows a top-front perspective view of the bag with the flap open.

FIG. 4 shows a top view of the bag with the flap open.

FIG. 5 shows a right-side view of the bag with the flap closed.

FIG. 6 shows a left-side view of the bag with the flap closed; and,

FIG. 7 shows a bottom view of the bag with the flap closed. The broken lines in the drawings illustrate portions of the bag that form no part of the claimed design.

1 Claim, 7 Drawing Sheets
